SIGN FLASHER

William H. Marshall, Jr., Cleveland, Ohio

Application April 12, 1930, Serial No. 443,717

5 Claims. (Cl. 177—346)

This invention relates to means for intermittently flashing an electric sign or the like.

One object of this invention is to provide an improved simplified device for supplying electric current to a sign or other electrical apparatus at regular intervals.

Other objects are to provide a device of this type operated by the current which feeds the sign, and one which is readily adaptable for use 10 with either direct or alternating current; to reduce the moving parts to a minimum; to utilize an electric discharge device as a timing element, and to provide means for adjusting the duration of the current flow and of the intervals therebetween.

Other objects relating to details of construction and assembly and economies of manufacture will appear hereinafter.

In the accompanying drawings:

Fig. 1 is a circuit diagram of the improved device arranged for operation with direct current.

Fig. 2 is a circuit diagram arranged for operation with alternating current.

Fig. 3 is an elevation of the improved device showing the assembly thereof on a panel.

Referring to Fig. 1 of the drawings, the reference numerals 10 and 11 designate, respectively, the positive and the negative input terminals which are adapted to be connected to a direct 30 current supply line such as is ordinarily used to illuminate signs. The main circuit passes directly from the terminals 10 and 11 through the fixed and movable contacts 12 and 13, respectively of a relay 14, to the output terminals 15 which are 35 connected to a sign, illustrated diagrammatically as a plurality of incandescent lamps 16.

The relay 14 is controlled through the medium of an electric discharge device 17, illustrated herein as a two element space discharge valve having 40 a filament 18 and a plate 19. The filament circuit is connected to the terminals 10 and 11, the negative side directly and the positive side through the contacts 12 and 13 of the relay and a resistance 20 which reduces the line voltage 45 to the correct value for proper operation of the valve 17. The positive side of the plate circuit passes through the windings of the relay 14 to the positive input terminal 10, the negative side of the filament circuit completing the plate circuit. 50 A variable resistance 21 of any suitable type, illustrated diagrammatically as a rheostat, is shunted across the windings of the relay 14, and a second rheostat 22 is placed in series with the relay windings.

The movable contact 13 of the relay is normal-

ly held in circuit closing position against the fixed contact 12 by gravity or a spring of any suitable type. Preferably a condenser 23 is connected across the contacts 12 and 13 to reduce sparking.

When the input terminals 10 and 11 are connected to the supply line, current flows through the relay contacts 12 and 13 to the sign lamps 16, and through the resistance 20 to the filament 18 of the valve. As the filament heats up, space current begins to flow to the plate 19 and through 10 the windings of the relay 14. When the space current reaches a predetermined value, the relay 14 retracts the movable contact 13 and breaks the sign and filament circuits. The plate circuit, however, is unaffected by the relay and the 15 space current continues to flow as the filament cools until, at a pre-determined minimum value, the movable contact 13 returns to circuit closing position and starts another cycle of operations.

As shown in Fig. 3, the movable contact 13 of the relay is carried by a spring arm 24 connected to a pivoted armature 25. The fixed contact 12 is carried by a screw 26 mounted on the base for adjustment toward or away from the relay magnets. The spring mounting of the contact 13 25 prevents flickering of the sign when the circuit is broken, since the initial weak space currents, which may move the armature slightly, do not interrupt the circuit.

The force required to hold the armature in 30 raised position is less than the force required to initially lift the same, since the effect of the magnetic flux varies inversely as the square of the distance. This differential measures the time during which the sign circuit is broken, and can 35 be adjusted as desired by varying the position of the fixed contact 12 with respect to the relay magnets. The rheostat 22 controls the resistance of the plate circuit, and the rheostat 21 controls the proportion of the space current which passes 40 through the relay windings. Adjustment of these rheostats varies the length of time the sign circuit is closed and the interval between flashes. It will thus be seen that the timing of the device can be adjusted at will within wide limits. 45

Fig. 2 illustrates the circuit diagram of the device designed for operation on alternating current. In this form the input terminals 10' are connected through the relay contacts 12 and 13 to the sign lamps 16 as in Fig. 1. The filament 18 of the valve 17 is fed at the proper voltage by the secondary windings of a step-down transformer 27, the primary windings of which are connected to the input terminals 10' through the contacts 12 and 13. The plate circuit passes 50 55

through the windings of the relay 14 to one side of the supply line, and through a center tap on the secondary of the transformer 27 to the other side of the supply line. Since the relay contacts 12 and 13 carry alternating current, the condenser 23 is connected across the relay windings, instead of across the contacts.

In this form of the device, the valve 17 rectifies the space current to provide direct current for operating the relay. In other respects the operation is substantially identical with the operation of the direct current circuit illustrated in Fig. 1.

In manufacturing the devices the elements are preferably assembled on a suitable base or panel, as illustrated in Fig. 3. In the alternating current type the transformer 27 is installed in place of the resistance 20 and the wiring rearranged slightly to accommodate the transformer and connect the condenser 23 across the relay windings. It will accordingly be seen that the manufacture and assembly of the two types of the device is facilitated, since the parts are largely interchangeable.

An important feature of the invention resides in the fact that the direct current circuit, as shown in Fig. 1, may also be operated satisfactorily by alternating current, since the resistance 20 will reduce the voltage of either direct or alternating current. Where alternating current is to be employed exclusively, however, the transformer is preferable, being less subject to heating and occupying less space than the resistance.

Although the foregoing description is necessarily of a detailed character in order that the invention may be fully set forth, it is to be understood that various modifications and rearrangements of parts may be resorted to without departing from the spirit or scope of the invention as defined in the following claims.

I claim:

1. In a sign flasher arranged to intermittently make and break the electric current for a sign or the like and to be actuated by such current, the combination of a relay having windings and armature controlled contacts, a sign load circuit passing through the contacts of said relay, an electrical discharge device including a filament with an appreciable temperature lag and an anode, a circuit for heating said filament passing through the contacts of said relay, a circuit passing through the windings of said relay and between said filament and said anode, all of said circuits being in parallel to receive current from a single source.

2. In a sign flasher arranged to intermittently make and break the electric current for a sign or the like and to be actuated by such current, the combination of a relay having windings and an armature controlled circuit breaker, a sign load circuit passing through the circuit breaker of said

relay and adapted to be connected to a source of electric current, an electrical discharge device having an anode and a filament cathode with an appreciable temperature lag, a cathode heating circuit passing through the circuit breaker of said relay, and an anode-cathode circuit passing through the windings of said relay, and an adjustable resistor shunted across the windings of said relay to control the proportion of current in the anode-cathode circuit which passes through the windings of the relay.

3. In a sign flasher arranged to intermittently make and break the electric current for a sign or the like and to be actuated by such current, the combination of a relay having windings and an armature controlled circuit breaker, a sign load circuit passing through the circuit breaker of said relay and adapted to be connected to a source of electric current, an electric discharge device having an anode and a filament cathode with an appreciable temperature lag, a cathode heating circuit passing through the circuit breaker of said relay, and an anode-cathode circuit passing through the windings of said relay, and an adjustable resistor in series with the windings of said relay for varying the resistance thereof.

4. In a sign flasher arranged to intermittently make and break the electric current for a sign or the like and to be actuated by such current, the combination of a direct current relay having windings and an armature controlled circuit breaker, a sign load circuit passing through the circuit breaker of said relay and adapted to be connected to a source of alternating current, an electric discharge device having an anode and a filament cathode with an appreciable temperature lag, a circuit for heating said cathode energized by said source of alternating current in parallel with said load circuit and passing through the circuit breaker of said relay and an anode-cathode circuit passing through the windings of said relay and connected to said source of alternating current to rectify the same to actuate said relay.

5. In a sign flasher arranged to intermittently make and break the electric current for a sign or the like and to be actuated by such current, the combination of a relay having windings and armature controlled contacts, a sign load circuit passing through the contacts of said relay, an electrical discharge device including a filament with an appreciable temperature lag and an anode, a circuit for heating said filament passing through the contacts of said relay, a circuit passing through the windings of said relay and between said filament and said anode, all of said circuits being in parallel to receive current from a single source, and a condenser across the windings of said relay.

WILLIAM H. MARSHALL, JR. 60
